UNITED STATES PATENT OFFICE.

HARRY H. HANCOCK, OF SWAMPSMOTT, MASSACHUSETTS.

EXTENSION FURNITURE FOR PRINTERS.

1,397,485.

Specification of Letters Patent.

Patented Nov. 15, 1921.

Application filed October 6, 1920. Serial No. 415,013.

To all whom it may concern:

Be it known that I, HARRY H. HANCOCK, a citizen of the United States, residing at Swampscott, in the county of Essex and State of Massachusetts, have invented certain new and useful Improvements in Extension Furniture for Printers, of which the following is a specification.

This invention relates to extension furniture for printers, and one object of the invention is to provide extension or adjustable furniture for securing type within a chase, said furniture being composed of counterpart members which are preferably inseparable from each other. Another object of the invention is to provide extension or adjustable furniture for printers, in which—although the separate members are preferably inseparable from each other—they are made to have uniform thickness in corresponding parts from end to end, thereby affording a support for the type that will be set against them on either side thereof; each member preferably being of pica measurement in length, as well as in breadth. The extension furniture of the present invention is preferably made for any size of chase. Other objects of the invention will appear herein.

The specified objects being among the objects of the present invention, the same consists of certain features of construction and combinations of parts to be hereinafter described and then claimed with reference to the accompanying drawings, showing one embodiment of the invention, in which:

Figure 1 is a perspective view of the improved printers' furniture showing the members collapsed or distended;

Fig. 2 is a perspective view showing the members partly extended or adjusted;

Fig. 3 is a transverse section; on line 3—3, Fig. 4;

Fig. 4 is a plan of one face of the furniture, partly broken away; and

Fig. 5 is a perspective view of one of the members of the furniture.

Referring to the drawings, there are two members 10 and 11, and the construction of these members is preferably such that they are counterparts of each other, or are twin members. The member 10 is provided with a longitudinal tongue 12, which is shown as of the same length as the body portion of the member 10. The member 11 has a similar tongue 13. As shown, the separate mem-

bers of the furniture are of compound construction, although in practice each member is preferably composed of one piece. When each member is of compound construction it will have opposite upper and lower walls 14, 15, and said walls receive between them an extended end of the corresponding tongue 12 or 13, as the case may be, and these extended ends are placed between the said walls 14, 15, the three elements being secured together, as by rivets 14^a, the ends of which are countersunk in the walls. In practice, it is preferred to spot-weld the walls 14, 15 to the extended end of each tongue, so that an integral structure is provided.

Each member composed of the walls 14, 15 and the part therebetween is provided with a longitudinal bore or hole 16, if that be desired, for the sake of securing lightness. Each member 10 or 11 is provided along one edge with a deep longitudinal recess 17, the bottom of which recess is preferably located at about the mid-width of each member. The recessed body portion of each member 10 and 11 is provided with an under-cut groove 18, which extends longitudinally thereof along one side of the body portion, and this recess is continued in the tongue 12 or 13 of the members. By under-cutting the body portion of each member 10 and 11, an overhang lip 19 is provided, which extends longitudinally of the body portion and longitudinally of the tongue.

The members of the extension or adjustable furniture, being counterparts of each other, preferably, the tongue of one member will be received in the longitudinal recess of the other member in such way that the under-cut groove 18 of each member will receive the overhang lip 19 of the other member. Therefore, the two members mutually engage each other, and each may slide upon the other for longitudinal contraction or longitudinal extension of the furniture. The engagement of each longitudinal lip 19 of one member with the longitudinal under-cut groove 18 of the other member will preclude transverse separation of the two members, and the width of the furniture will always, in this preferred embodiment of the invention, be maintained uniform throughout the furniture. For the purpose of preventing longitudinal separation of the two members, one member is provided with a longitudinal groove 20, in which engages a pin or tongue 21 on the other member, said

pin being located at a suitable distance inside the inner end of its member so that when the members are fully extended, the said pin will engage the adjacent end or 5 shoulder of the longitudinal groove 20.

It will therefore be seen that the described adjustable furniture is preferably composed of two members which are inseparable from each other, and which cannot be separated 10 transversely from each other. In other words, each piece of furniture preferably constitutes a unit, the parts of which will always be assembled. In cross section, the furniture is preferably rectangular, and will 15 at least have square edges which are parallel, so that the furniture may be properly set up against the type and the chase. It will be observed that it is not necessary to make use of friction for binding the parts 20 of the furniture together, inasmuch as they are preferably always held together so that they can be handled as a unit.

The opposite faces of the body portions 25 of the two members are preferably provided with transverse ribs 22, 23, which are spaced at suitable distances apart. These ribs serve to reinforce the structure of each member of the furniture transversely; that is, they give transverse strength where the 30 pressure is applied in the chase. The ribs which rest upon the imposing surface also serve to raise the furniture thereabove to reduce the friction with such surface in adjusting the furniture, and the furniture may 35 be conveniently adjusted by the engagement of the fingers of the printer with the upper transverse ribs, or the shoulders formed thereby. The ribs or shoulders 22, 23 provide means for accomplishing the several 40 ends referred to, and provide a practical structure for otherwise light furniture.

Each member of the furniture is preferably made of pica measurement from edge to edge, and of pica measurement longitudinally. 45

It will be seen that in the specific form of the invention illustrated, the adjacent surfaces of the extension members lie in contact throughout when the members are collapsed. Consequently, except for such 50 bores 16 in the members as tend to lighten them, the said members are practically solid transversely. It will furthermore be seen that the groove or slot 20 in one of the members 55 provides at the extreme inner end of that member a stop-shoulder for the tongue or pin 21, so that both members can be extended for substantially their full length, but cannot be separated by their longitudinal 60 extension. Also, the engaged extension members of the furniture are longitudinally divided in counterpart halves at the plane of separation formed by the undercut recess in one member and the lip of the other member. More specifically, the undercut 65

recesses and the lips of the two members engage each other for the purpose of preventing transverse separation of the members, substantially coincident with the longitudinal axis of the furniture. 70

It is obvious that the invention is susceptible of more or less modification, as parts may be omitted, parts added, and parts modified, without departing from the scope and spirit of the invention, as defined 75 in the claims; as for instance, the upper and lower faces of the furniture may be plain throughout the length of the furniture, except that, for instance, countersunk depressions at suitable intervals may be formed 80 in said faces, and such depressions will enable the several functions which are accomplished by the transverse ribs to be gained in perhaps as desirable a manner. 85

What I claim is:

1. Extension furniture for printers constituting a complete article of manufacture of a size adapted for use in a chase, comprising two elongated mutually engaged counterpart members, each of said members having 90 at adjacent vertical walls a longitudinal recess and a longitudinal under-cut groove in the inner wall of said recess, and said groove providing a longitudinal lip, said lips being located in said grooves and in contact 95 throughout approximately the longitudinal, central, vertical plane of said furniture.

2. Extension furniture for printers, comprising two mutually engaged members, each having a body portion with the transverse 100 dimensions required in use, and a longitudinal tongue on each member, extended from one wall thereof, the other wall of each member having a longitudinal, longitudinally under-cut recess, the bottom of which 105 recess extends along the line of the inside wall of the corresponding tongue, while said longitudinal under-cut extends along said inside wall, the under-cut forming a longitudinal lip on each body portion and its 110 tongue, and said lips being in interlocking engagement to preclude transverse separation of the mutually engaged members, the said engaged members being longitudinally divided in substantially counterpart halves 115 at the said undercut recess and lip.

3. Extension furniture for printers, comprising two mutually engaged members, each having a body portion with the transverse dimensions required in use, and a longitudinal tongue on each member, extended from one wall thereof, the other wall of each member having a longitudinal, longitudinally under-cut recess, the bottom of which 120 recess extends along the line of the inside wall of the corresponding tongue, while said longitudinal under-cut extends along said inside wall, the under-cut forming a longitudinal lip on each body portion and its tongue, and said lips being in interlocking 125

engagement to preclude transverse separation of the mutually engaged members along a line longitudinally dividing the furniture into two substantially equal parts, the tongue 5 of each member solidly filling the recess of the other member, and means for preventing the longitudinal separation of said members.

4. Extension furniture for printers, comprising two mutually engaged members, each 10 having a body portion with the transverse dimensions required in use, and a longitudinal tongue on each member, extended from one wall thereof, the other wall of each member having a longitudinal, longitudinally 15 under-cut recess, the bottom of which recess extends along the line of the inside wall of the corresponding tongue, while said longitudinal under-cut extends along said inside portion and its tongue, and said lips being in 20 interlocking engagement to preclude transverse separation of the mutually engaged members, and a tongue-and-groove connec-

tion between said members for preventing longitudinal separation thereof.

5. Extension furniture for printers, comprising two mutually engaged members, each 25 having a body portion with the transverse dimensions required in use, and a longitudinal tongue on each member, extended from one wall thereof, the other wall of each member having a longitudinal, longitudinally under-cut recess, the bottom of which recess extends along the line of the inside wall of the corresponding tongue, while said longitudinal under-cut extends along said inside 30 portion and its tongue, and said lips being in 35 interlocking engagement to preclude transverse separation of the mutually engaged members, and a tongue-and-groove connection 40 between said members for preventing longitudinal separation thereof, said members having shoulders for engagement by the fingers for adjusting the members.

HARRY H. HANCOCK.
